A. P. PORTER,
PORTABLE SAFETY DOOR LOCK,
APPLICATION FILED FEB. 12, 1919.

1,334,399.

Patented Mar. 23, 1920.

Inventor
A. P. Porter.
Attorney
J. Haileg, Jr.

UNITED STATES PATENT OFFICE.

ALFRED PALMER PORTER, OF AMIDON, NORTH DAKOTA.

PORTABLE SAFETY DOOR-LOCK.

1,334,399.

Specification of Letters Patent. Patented Mar. 23, 1920.

Application filed February 12, 1919. Serial No. 276,570.

To all whom it may concern:

Be it known that I, ALFRED PALMER PORTER, a citizen of the United States, residing at Amidon, in the county of Slope and State of North Dakota, have invented certain new and useful Improvements in Portable Safety Door-Locks; and I do hereby declare the following to be a full, clear, and exact description of the invention, such as will enable others skilled in the art to which it appertains to make and use the same.

My invention relates to improvements in portable safety door locks.

An important object of this invention is to provide a lock of the character described, adapted for immediate attachment to a door to securely lock the same closed.

A further object of the invention is to provide a lock of the character described, which is compact and of highly simplified construction, thus permitting its use by travelers and others desiring to carry the lock from place to place.

A further object of the invention is to provide a lock of the character described, which is neat in appearance, few in parts and cheap to manufacture.

A further object of the invention is to provide a lock of the character described, which by virtue of its compact construction and cheapness of manufacture will meet with commercial favor when placed upon the market.

Other objects and advantages of the invention will be apparent during the course of the following description.

In the accompanying drawing, forming a part of this specification, and in which like numerals are employed to designate like parts throughout the same,

Figure 1 is a side elevation of a lock embodied in my invention, the same being shown applied to a door,

Fig. 2 is a plan view of the same, applied to a door, a portion of the door being broken away, and

Fig. 3 is a bottom plan view of the lock, showing the same in a folded position.

In the drawing, wherein for the purpose of illustration is shown the preferred embodiment of my invention, the numeral 5 generically designates my improved lock, which in manufacture may be made of any desired metal, preferably a light durable metal. My improved lock comprises, in part, a door contact plate 6, adapted for at-

achment to the inner side of a door near the lower portion thereof and is provided with a flange 7, contacting with the under side of the door. Secured to the outer side of the door contact plate is a relatively small plate 8', having its upper portion bent to form a hinge barrel 8. A lever 9 has its rear end portion bent upon itself to form a hinge barrel 10 alining with the hinge barrel 8. The hinge barrels 8 and 10 are adapted for the reception of a pin 11, thus permitting of a pivotal movement of the lever 9. The under side of the lever 9 is provided with a relatively small plate 12 at its rear end portion. The forward end portion of the plate 12 is bent upon itself to form a hinge barrel 13. A retaining arm 14, having its rear end portion bent upon itself to form hinge barrels 15 adapted to aline with the hinge barrel 13. The hinge barrels 13 and 15 are adapted for the reception of a pin 16, effecting a pivot for the arm 14. The forward end portion of the arm 14 is provided with floor-engaging claws 17. The forward end portion of the lever 9 is reduced and curved upon itself to provide a barrel for receiving a handle 18.

In applying my improved lock to a door, it will be apparent that the door contact element 6 is applied to the lower portion of the door approximately in line with the latch and the arm 14 engaged with the floor, as shown in dotted lines in Fig. 1. To lock the device, the forward end portion of the lever 9 is pressed downwardly, thus forcing the claws 17 into the floor. It will be apparent that any pushing from the outside of the door will cause the claws 17 to be forced still farther into the floor. To release the lock, the handle 18 is pulled upwardly, thus drawing the claws from the floor in approximately the same line of their entrance.

While I have shown and described the preferred embodiment of my invention, it is understood that I may make such minor changes in arrangement and construction of parts, as will remain within the spirit of the invention and the scope of the appended claim.

Having thus described my invention, what I claim is:

A portable door lock comprising a plate adapted for attachment to the lower portion of a door, a flange carried by said plate for engagement with the under side of the door,

a lever hinged to said plate by its upper end portion and having its lower end portion formed to receive a handle, a handle mounted in said lower end of the lever, a retaining arm pivoted to the under face of said plate adjacent to the upper end of the latter, the lower end of said retaining arm extending past the lower end of said plate and carrying floor engaging members for biting engagement with the floor surface adjacent to the door when said plate and said retaining arm are in parallel relation, said handle

serving as means for moving said lever and said retaining arm into parallel relation and for swinging upwardly the said lever and said arm to disengage said retaining arm from engagement with the floor surface. 15

In testimony whereof I affix my signature in presence of two witnesses.

ALFRED PALMER PORTER.

Witnesses:

T. E. PURCELL,
A. B. LANDQUIST.
